UNITED STATES PATENT OFFICE.

CHARLES HENRY BIGGS, OF LONDON, ENGLAND.

METHOD OF MAKING HORMS FOR SOUND-REPRODUCING APPARATUS.

Application filed July 29, 1926, Serial No. 125,830, and in Great Britain August 12, 1925.

This invention relates to horns for sound reproducing apparatus and has for its object a simple method for manufacturing same.

According to this invention I manufacture such horns with strips of paper, fabric or like material.

The accompanying drawing illustrates a horn made in accordance with my invention.

In one manner of carrying out this invention concerning horns made of paper, I use strips of paper gummed or provided on one or both sides with an adhesive and spirally wound into flat reels or discs so that they may be drawn axially in the shape of a 15 tapering tube or sound conduit. I have found that when the reels are wound under proper tension the sound conduits formed in this manner can be easily bent to any desired curvature. For example when it is 20 desired to form a horn with a mouthpiece more or less at right angles to the stem the coil is slightly unwound to obtain the proper tension as it is pulled out and bent whereby even overlapping of the convolutions 25 at the bend or bends can be obtained. The overlapping on the greater radius of the bend is less than that on the smaller radius and consequently transverse reinforcements *a* and *b* are provided on the outer circumference in order to prevent the overlapping convolutions from becoming distorted. The diameter of the horn increases 30 gradually from the commencement of the sound conduit to the end of the flare, the largest diameter being that of the original 35 reel or disc of paper. When the sound conduit so formed has been given the correct form required, it is wetted and the turns become fixed in position by the adhesive 40 with which the strip is coated. The horn

so formed is then provided with a protective coating, that is to say painted, and/or varnished as desired.

It has been found advantageous to coat the horn with a mixture of plaster of Paris 45 and glue before painting and/or varnishing.

A horn made by the method described above is very light and very cheap; and is admirably suited for internal horns for enclosed loud speakers or gramophones; it 50 is absolutely non-resonant.

It is obvious that any material which can be obtained in strip form, or any fabric can be used instead of paper.

What I claim and desire to secure by 55 Letters Patent is:—

Method of making a horn for gramophones, loud speakers and the like apparatus, consisting in spirally winding strips of material, such as, for example, paper or 60 fabric, into flat reels, the said strips being gummed on at least one side, drawing the said reels axially in the shape of a tapering tube or sound conduit so that the convolutions overlap, the coil being slightly un- 65 wound during the drawing operation, bending the tube thus formed to the desired curvature, wetting the tube thus formed so as to fix the turns in position by the adhesive with which the strip is coated, coating the horn with a mixture of plaster of Paris and glue, plastering at least one strip of fabric such as an ordinary medical bandage transversely of the turns where the overlapping is reduced and providing the horn 70 thus formed with a protective coating.

In testimony whereof, I affix my signature.

CHARLES HENRY BIGGS.
